HYDROCARBON CONVERSION

Bernardus Sellmeyer, Leonia, N. J., assignor to
The M. W. Kellogg Company, Jersey City, N. J.,
a corporation of Delaware

Application November 30, 1940, Serial No. 367,932

12 Claims. (Cl. 260—683.4)

This invention relates to the alkylation of low molecular weight paraffinic hydrocarbons with low molecular weight olefinic hydrocarbons to produce paraffinic hydrocarbons of higher molecular weight suitable for use as gasoline motor fuel. More particularly, the invention relates to the alkylation of isoparaffinic hydrocarbons such as isobutane with low molecular weight olefinic hydrocarbons such as butenes and propylene to produce paraffinic hydrocarbons boiling within the gasoline boiling range and of high anti-knock value.

Sulfuric acid is employed to catalyze the alkylation of low molecular weight paraffinic hydrocarbons such as isobutane with butenes and propylene. The raw material ordinarily employed in carrying out such an operation is a mixture of hydrocarbon gases such as those produced by oil cracking operations which contain the desired reactants. These gaseous mixtures ordinarily predominate in paraffinic and olefinic hydrocarbons having three and four carbon atoms per molecule. Such a mixture may be employed as such as fresh feed to the alkylation process, or a selected fraction may be employed which predominates in C₄ hydrocarbons and contains only a small proportion of C₃ hydrocarbons. In any event, however, the use of the raw materials which are available for this process involves the introduction into the process of a definite proportion of low-boiling hydrocarbons such as propane which are not suitable as reactants for the alkylation reaction. The presence of these hydrocarbons such as propane in the reaction zone is not in itself harmful to the reaction. In the continuous processes which are ordinarily employed, with recycling of isobutane, the presence of a small proportion of these low-boiling hydrocarbons such as propane in the reaction zone may be desirable. However, they tend to accumulate in the system to excessive proportions unless measures are taken for continuous or periodical removal of them from the system.

It is an object of this invention to provide an alkylation process, employing a fresh feed containing low-boiling hydrocarbons such as propane which are non-reactive in the alkylation reaction, in which such non-reactive hydrocarbons are eliminated from the system in a novel and efficient manner.

The invention will be described by reference to the accompanying flow diagram which illustrates an application of the invention to a process for the alkylation of isobutane with butenes and

possibly propylene. It is to be understood, however, that the invention is not limited to the specific modification illustrated by the drawing but is capable of other modifications, as will be apparent to those skilled in the art.

In describing the invention by reference to the specific modification illustrated by the drawing reference will be made to the treatment of a raw material consisting predominantly of hydrocarbons having four carbon atoms per molecule and containing a minor proportion of C₃ hydrocarbons. It is to be understood, however, that the invention is not limited to the treatment of a raw material of this description but is applicable to the treatment of raw materials containing larger proportions of C₃ and lighter hydrocarbons and also is applicable to the treatment of raw materials containing substantial proportions of hydrocarbons having five or more carbon atoms per molecule.

Referring to the drawing, the alkylation reaction is carried out in reactor 1 in which isobutane, normal butane, propane, butenes and sulfuric acid are intimately mixed. A mixture of these materials is introduced into reactor 1 through line 2, and suitable means are provided for effecting intimate mixing of the reactants in reactor 1. For example, line 3 provided with pump 4 may be provided for continuously withdrawing a mixture of the reactants, sulfuric acid and liquid products from one portion of the reactor and reintroducing it at another portion thereof. A portion of the mixture withdrawn from reactor 1 through line 3 is continuously diverted through line 5 which connects with separator 6. In separator 6 the mixture is permitted to separate into an upper layer of alkylate and unreacted gas and a lower layer of acid.

The acid separated in separator 6 is continuously withdrawn through line 2, provided with pump 7, and returned to reactor 1. A portion of this acid is diverted from line 2 through line 8 and withdrawn from the system as spent acid. The acid thus withdrawn through line 8 is replaced by fresh acid introduced to the system through line 9, provided with pump 10, which connects with line 2.

The mixture of alkylate and normally gaseous hydrocarbons which separates in the upper portion of separator 6 is withdrawn continuously through line 11, provided with pump 12, which connects with isobutane fractionator 13. In fractionator 13 conditions of temperature and pressure are maintained for effecting separation of

a condensate in the lower portion thereof containing the alkylate product and normal butane. The mixture of alkylate and normal butane is withdrawn from fractionator 13 through line 14 for further treatment for the recovery of the butane and the gasoline constituents of the alkylate. A gas fraction predominating in isobutane passes overhead and is withdrawn from fractionator 13 through line 15. Line 15 connects with condenser 16 wherein means are provided for effecting condensation of the gas. The condensate thus obtained is withdrawn from condenser 16 through line 17 provided with pump 18. A portion of this condensate is diverted from line 17 through line 19 and returned to fractionator 13 as reflux.

Line 17 connects with line 2 at a point intermediate the junction of lines 2 and 9 and the entrance of reactor 1 in order to effect recycling of the isobutane fraction to the reaction.

Reactor 1 is operated under conditions which permit continuous evaporation of unreacted gases in order to effect cooling of the reaction mixture and maintain it at the desired reaction temperature. For example, in effecting alkylation of isobutane with butenes or their dimers or trimers it is desirable to have in reactor 1 an amount of a lighter gas such as propane which will promote vaporization.

The gas mixture thus evaporated in reactor 1 is withdrawn therefrom through line 18 provided with a compressor 19 and cooler 20. By means of compressor 19 and cooler 20 the gases are compressed and substantially condensed. Whether or not all of the gases are condensed depends upon the desired method of operation and on the quantity of light hydrocarbons such as propane in the mixture. The condensate and any accompanying uncondensed gases are introduced from line 18 into a separator or accumulator 21. Condensate collected at 21 is withdrawn therefrom through line 22, provided with a pump 23, and reintroduced into reactor 1.

If substantially all the gases withdrawn from reactor 1 through line 18 are condensed at 19 and 20 a portion of the condensate in line 22 is diverted therefrom through line 24 provided with pump 25. Line 24 connects with a depropanizer fractionator 26. Fractionator 26 is operated under conditions of temperature and pressure to separate as a condensate materials desired as reactants in reactor 1 and to separate overhead a gas containing a sufficient quantity of propane and other light hydrocarbons present to prevent the accumulation of these gases in the reaction zone to an excessive amount. When operating at equilibrium conditions the amount of these gases must equal the amount introduced with the fresh feed. The gas thus separated passes overhead in fractionator 26 and is withdrawn therefrom and from the system through line 27. The condensate collected in the lower portion of fractionator 26 is withdrawn therefrom through line 28 which connects with line 2 whereby the condensate is recycled to the alkylation reaction.

If a substantial proportion of the gases withdrawn from reactor 1 through line 18 remains uncondensed after passage through compressor 19 and cooler 20 these uncondensed gases are separated at 21 and withdrawn therefrom through line 29 which connects with line 24 whereby the gases are introduced into fractionator 26 for treatment in the manner de-

scribed above. If depropanizer 26 is operated at a higher pressure than separator 21 it will be desirable to provide a compressor 30 in line 29 to effect transfer of the gases to fractionator 26.

The fresh feed to the process which, for example, consists mainly of C₄ hydrocarbons and a small proportion of C₃ hydrocarbons is introduced into the system through line 31 provided with a pump 32. Line 31 connects with line 2 whereby the fresh feed may be introduced directly into reactor 1. Alternatively, and preferably if the fresh feed contains more C₃ hydrocarbons than are desired in reactor 1, the fresh feed may be introduced into fractionator 26 by means of line 33 which connects line 31 with line 24. If the fresh feed is introduced into the fractionator 26 it is subjected to fractionation in the manner described to separate a condensate containing the proportion of C₃ hydrocarbons which it is desired to introduce into reactor 1.

The fresh feed may contain all the isobutane which is consumed in the process, or all or a portion of this material may be introduced from a separate source through line 34 which connects with line 2. The fresh feed may also contain the olefinic reactants which are consumed in the process, or all or a portion of these may be introduced from a separate source. For example, butenes or their dimers or trimers may be introduced into the system through line 35 which connects with line 2. In addition any desired fraction of the alkylate may be recycled to the reaction zone.

In reactor 1 it is preferred to maintain a ratio of isobutane to butenes which is greater than 1. For example, the feed to the reactors introduced through line 2 along with the acid may consist, in mol per cent, of 60 to 65 per cent isobutane, 12 to 15 per cent butenes, 18 to 22 per cent normal butane and 2 to 5 per cent C₃ hydrocarbons.

Reactor 1 is operated preferably at a pressure not substantially greater than atmospheric, for example, 5 pounds gauge and at the desired reaction temperature, for example, 40° F.

The alkylate and butanes are fractionated in fractionator 13 preferably at a suitably higher pressure, for example, 100 to 120 pounds per square inch.

The gases withdrawn from reactor 1 through line 18 are compressed to a pressure which will vary depending upon the amount of C₃ and lighter hydrocarbons which are contained in the gas. Under ordinary operations these gases are compressed to a pressure of 80 pounds per square inch or higher.

Depropanizer fractionator 26 ordinarily is operated at a substantially higher pressure in order to obtain the desired separation. For example, in this fractionator a pressure of 200 pounds per square inch may be maintained.

The invention provides an alkylation process for the treatment of raw materials containing reactions desired for the process and in addition hydrocarbons which are lower boiling than the reactants. In accordance with this process such low-boiling hydrocarbons are utilized in the reaction zone to effect the necessary cooling and are then eliminated from the system in order to prevent their accumulation to an undesired degree. The method for the elimination of these light hydrocarbons provided by the present proc-

ess involves the fractionation treatment of a mixture which contains the maximum concentration of these light hydrocarbons, thus reducing to a minimum the apparatus requirements of the process and the consumption of energy.

The invention has been described by reference to a specific application of it to a specific process. It is to be understood, however, that the invention is capable of other applications in connection with other modifications of the alkylation process of the general type described herein.

I claim:

1. A process for alkyllating low molecular weight paraffinic hydrocarbons with low molecular weight olefinic hydrocarbons to form paraffinic hydrocarbons which comprises introducing into an alkylation reaction zone sulfuric acid alkylation catalyst and hydrocarbons comprising low molecular weight hydrocarbons suitable as alkylation reactants and lower boiling hydrocarbons unsuitable as alkylation reactants, maintaining said reaction zone at alkylation conditions of temperature and pressure effective to vaporize unreacted hydrocarbons including said lower boiling hydrocarbons to facilitate maintaining the reactants in the reaction zone at the desired reaction temperature, withdrawing said vaporized hydrocarbons from said reaction zone, cooling said vaporized hydrocarbons externally of said reaction zone to condense at least a portion thereof, reintroducing into said reaction zone as condensate a portion of said cooled hydrocarbons, introducing another portion of said cooled hydrocarbons into a fractionating zone, maintaining conditions in said fractionating zone effective to separate said last-mentioned portion of the cooled hydrocarbons into a condensate fraction containing the constituents of said last-mentioned portion of the cooled hydrocarbons which are suitable as reactants in the alkylation reaction and a vapor fraction containing lower boiling hydrocarbons unsuitable as reactants for the alkylation reaction, introducing said condensate fraction into said reaction zone, and withdrawing said vapor fraction from the system.

2. A process for alkyllating low molecular weight paraffinic hydrocarbons with low molecular weight olefinic hydrocarbons to form paraffinic hydrocarbons which comprises (continuously) introducing into an alkylation reaction zone sulfuric acid alkylation catalyst and hydrocarbons comprising low molecular weight hydrocarbons suitable as alkylation reactants and lower boiling hydrocarbons unsuitable as alkylation reactants, maintaining said reaction zone at alkylation conditions of temperature and pressure effective to vaporize unreacted hydrocarbons including said lower boiling hydrocarbons to facilitate maintaining the reactants in the reaction zone at the desired reaction temperature, continuously withdrawing said vaporized hydrocarbons from said reaction zone, cooling said vaporized hydrocarbons externally of said reaction zone to condense at least a portion thereof, continuously reintroducing into said reaction zone as condensate a portion of said cooled hydrocarbons, introducing another portion of said cooled hydrocarbons into a fractionating zone, maintaining conditions in said fractionating zone effective to separate said last-mentioned portion of the cooled hydrocarbons into a condensate fraction containing the constituents of said last-mentioned portion of the cooled hydrocarbons which are suitable as reactants in the alkylation reaction and a vapor

fraction containing lower boiling hydrocarbons unsuitable as reactants for the alkylation reaction, continuously introducing said condensate fraction into said reaction zone, withdrawing said vapor fraction from the system, and continuously withdrawing from the alkylation reaction zone a liquid containing the alkylation product.

3. A process for alkyllating low molecular weight paraffinic hydrocarbons with low molecular weight olefinic hydrocarbons to form paraffinic hydrocarbons which comprises introducing into an alkylation reaction zone sulfuric acid alkylation catalyst and hydrocarbons comprising low molecular weight hydrocarbons suitable as alkylation reactants and lower boiling hydrocarbons unsuitable as alkylation reactants, maintaining said reaction zone at alkylation conditions of temperature and pressure effective to vaporize unreacted hydrocarbons including said lower boiling hydrocarbons to facilitate maintaining the reactants in the reaction zone at the desired reaction temperature, withdrawing said vaporized hydrocarbons from said reaction zone, cooling said vaporized hydrocarbons externally of said reaction zone to effect condensation thereof, reintroducing into said reaction zone a portion of the condensate thus obtained, introducing another portion of said condensate into a fractionating zone, maintaining conditions in said fractionating zone effective to separate said last-mentioned portion of the condensate into a condensate fraction containing the constituents introduced into said fractionating zone which are suitable as reactants in the alkylation reaction and a vapor fraction containing lower boiling hydrocarbons unsuitable as reactants for the alkylation reaction, introducing said condensate fraction into said reaction zone, and withdrawing said vapor fraction from the system.

4. A process for alkyllating low molecular weight paraffinic hydrocarbons with low molecular weight olefinic hydrocarbons to form paraffinic hydrocarbons which comprises introducing into an alkylation reaction zone sulfuric acid alkylation catalyst and hydrocarbons comprising low molecular weight hydrocarbons suitable as alkylation reactants and lower boiling hydrocarbons unsuitable as alkylation reactants, maintaining said reaction zone at alkylation conditions of temperature and pressure effective to vaporize unreacted hydrocarbons including said lower boiling hydrocarbons to facilitate maintaining the reactants in the reaction zone at the desired reaction temperature, withdrawing said vaporized hydrocarbons from said reaction zone, cooling said vaporized hydrocarbons externally of said reaction zone to condense a portion thereof, introducing into said reaction zone the condensate thus obtained, introducing the undissolved portion of said vaporized hydrocarbons into a fractionating zone, maintaining conditions in said fractionating zone effective to separate hydrocarbons introduced therein into a condensate fraction containing constituents introduced into said fractionating zone which are suitable as reactants in the alkylation reaction and a vapor fraction containing lower boiling hydrocarbons unsuitable as reactants for the alkylation reaction, introducing said condensate fraction into said reaction zone, and withdrawing said vapor fraction from the system.

5. A process for alkyllating low molecular weight paraffinic hydrocarbons with low molec-

ular weight olefinic hydrocarbons to form paraffinic hydrocarbons which comprises introducing into an alkylation reaction zone sulfuric acid alkylation catalyst and hydrocarbons comprising isobutane, propane and olefinic hydrocarbons reactive with the isobutane, maintaining said reaction zone at alkylation conditions of temperature and pressure effective to vaporize unreacted hydrocarbons including propane to facilitate maintaining the reactants in the reaction zone at the desired reaction temperature, withdrawing said vaporized hydrocarbons from said reaction zone, cooling said vaporized hydrocarbons externally of said reaction zone to condense at least a portion thereof, reintroducing into said reaction zone as condensate a portion of said cooled hydrocarbons, introducing another portion of said cooled hydrocarbons into a fractionating zone, maintaining conditions in said fractionating zone effective to separate hydrocarbons introduced therein into a condensate fraction containing the isobutane therein and a vapor fraction containing propane, introducing said condensate fraction into said reaction zone, and withdrawing said vapor fraction from the system.

6. A process for alkylating low molecular weight paraffinic hydrocarbons with low molecular weight olefinic hydrocarbons to form paraffinic hydrocarbons which comprises introducing into an alkylation reaction zone sulfuric acid alkylation catalyst and hydrocarbons comprising low molecular weight hydrocarbons suitable as alkylation reactants and lower boiling hydrocarbons unsuitable as alkylation reactants, maintaining said reaction zone at alkylation conditions of temperature and pressure effective to vaporize unreacted hydrocarbons including said lower boiling hydrocarbons to facilitate maintaining the reactants in the reaction zone at the desired reaction temperature, withdrawing said vaporized hydrocarbons from said reaction zone, cooling said vaporized hydrocarbons externally of said reaction zone to condense at least a portion thereof, reintroducing into said reaction zone as condensate a portion of said cooled hydrocarbons, introducing another portion of said cooled hydrocarbons into a fractionating zone, maintaining conditions in said fractionating zone effective to separate said last-mentioned portion of the cooled hydrocarbons into a condensate fraction containing the constituents of said last-mentioned portion of the cooled hydrocarbons which are suitable as reactants in the alkylation reaction and a vapor fraction containing lower boiling hydrocarbons unsuitable as reactants for the alkylation reaction, introducing said condensate fraction into said reaction zone, withdrawing said vapor fraction from the system, withdrawing from the reaction zone a liquid containing alkylation reaction products and lower boiling hydrocarbons suitable as reactants for the alkylation reaction, treating the liquid thus withdrawn from the reaction zone to separate therefrom a fraction containing the alkylation product and a lower boiling fraction containing hydrocarbons suitable as reactants in the alkylation reaction, and introducing said last-mentioned lower boiling fraction into said reaction zone.

7. A process for alkylating low molecular weight paraffinic hydrocarbons with low molecular weight olefinic hydrocarbons to form paraffinic hydrocarbons which comprises introducing into an alkylation reaction zone sulfuric acid alkylation catalyst and hydrocarbons comprising isobutane, normal butane, propane and olefinic

hydrocarbons reactive with isobutane, maintaining said reaction zone at alkylation conditions of temperature and pressure effective to vaporize unreacted hydrocarbons including propane to facilitate maintaining the reactants in the reaction zone at the desired temperature, withdrawing said vaporized hydrocarbons from said reaction zone, cooling said vaporized hydrocarbons externally of said reaction zone to condense at least a portion thereof, reintroducing into said reaction zone as condensate a portion of said cooled hydrocarbons, introducing another portion of said cooled hydrocarbons into a fractionating zone, maintaining conditions in said fractionating zone effective to separate a condensate fraction containing the isobutane introduced into said fractionating zone and a vapor fraction containing propane, introducing said condensate fraction into said reaction zone, withdrawing said vapor fraction from the system, withdrawing from said reaction zone a hydrocarbon mixture containing alkylation reaction product, normal butane and isobutane, fractionating the last-mentioned hydrocarbon mixture to separate therefrom a low-boiling hydrocarbon fraction predominating in isobutane, and introducing said last-mentioned fraction into said reaction zone.

8. A process for alkylating low molecular weight paraffinic hydrocarbons with low molecular weight olefinic hydrocarbons to form paraffinic hydrocarbons which comprises introducing into an alkylation reaction zone sulfuric acid alkylation catalyst and a fresh feed comprising isobutane, normal butane, propane and butenes, maintaining said reaction zone at alkylation conditions of temperature and pressure effective to vaporize unreacted hydrocarbons including propane to facilitate maintaining the reaction zone at the desired reaction temperature, withdrawing said vaporized hydrocarbons from said reaction zone, cooling said vaporized hydrocarbons externally of said reaction zone to condense at least a portion thereof, reintroducing into said reaction zone as condensate a portion of said cooled hydrocarbons, introducing another portion of said cooled hydrocarbons into a fractionating zone, fractionating the hydrocarbons introduced into said fractionating zone into a condensate fraction containing substantially all the isobutane introduced into said fractionating zone and a vapor fraction containing propane and substantially free from isobutane, introducing said condensate fraction into said reaction zone, and withdrawing said vapor fraction at a rate effective to withdraw from the system propane in an amount equivalent to the amount of propane introduced into the system as part of the fresh feed.

9. A process for alkylating low molecular weight paraffinic hydrocarbons with low molecular weight olefinic hydrocarbons to form paraffinic hydrocarbons which comprises introducing a fresh feed comprising isobutane, normal butane, propane and butenes into a fractionating zone, fractionating hydrocarbons introduced into said fractionating zone to separate a condensate fraction containing propane and substantially all the isobutane introduced into said fractionating zone and a vapor fraction containing propane and substantially free from isobutane, introducing said condensate fraction and sulfuric acid alkylation catalyst into an alkylation reaction zone, maintaining said reaction zone at alkylation conditions of temperature and pressure effective to vaporize unreacted hydrocarbons in-

cluding propane to facilitate maintaining the reaction zone at the desired reaction temperature, withdrawing said vaporized hydrocarbons from said reaction zone, cooling said vaporized hydrocarbons externally of said reaction zone to condense at least a portion thereof, reintroducing into said reaction zone as condensate a portion of said cooled hydrocarbons, introducing another portion of said cooled hydrocarbons into said fractionating zone, and withdrawing said vapor fraction separated in said fractionating zone at a rate effective to remove propane from the system in an amount equivalent to the amount of propane introduced into the system as part of the fresh feed.

10. A process for alkylating a low molecular weight isoparaffin hydrocarbon with a low molecular weight olefin hydrocarbon in the presence of a liquid acid catalyst to form a higher-boiling paraffin hydrocarbon which comprises maintaining a liquid body comprising an intimate mixture of hydrocarbon reactants and acid catalyst and containing said low molecular weight isoparaffin hydrocarbons in a substantially high ratio to said olefin hydrocarbons, continuously withdrawing a portion of said liquid mixture containing hydrocarbons, continuously charging to said liquid mixture hydrocarbon fresh feed comprising said low molecular weight isoparaffin and olefin hydrocarbons and lower-boiling normal paraffin hydrocarbons, maintaining the liquid mixture at alkylation conditions of temperature and pressure which permit vaporization of said unreacted isoparaffin hydrocarbons and said lower-boiling normal paraffin hydrocarbons to facilitate maintaining the liquid mixture at the desired reaction temperature, withdrawing the vaporized hydrocarbons from said liquid mixture, cooling and condensing hydrocarbons thus withdrawn, reintroducing condensate thus obtained into said liquid mixture, fractionating a portion of said vaporized hydrocarbons other than the condensate reintroduced into the liquid mixture to separate said last-mentioned portion of said vaporized hydrocarbons into a condensate containing isoparaffin hydrocarbons and a vapor containing said lower-boiling normal paraffin hydrocarbons, reintroducing said last-mentioned condensate into said liquid mixture, and withdrawing said last-mentioned vapor from the operation.

11. A process for alkylating isobutane with a low molecular weight olefin hydrocarbon in the presence of a liquid acid catalyst to form a higher-boiling paraffin hydrocarbon which comprises maintaining a liquid body comprising an intimate mixture of hydrocarbon reactants and acid catalyst and containing isobutane hydrocarbons in a substantially high ratio to said olefin hydrocarbons, continuously withdrawing a portion of said liquid mixture containing hydrocarbons, continuously charging to said liquid mix-

ture a hydrocarbon fresh feed comprising said low molecular weight olefin hydrocarbons, isobutane and propane, maintaining the liquid mixture at alkylation conditions of temperature and pressure which permit vaporization of propane and unreacted isobutane to facilitate maintaining the liquid mixture at the desired reaction temperature, withdrawing the vaporized hydrocarbons from said liquid mixture, cooling and condensing hydrocarbons thus withdrawn, reintroducing condensate thus obtained into said liquid mixture, fractionating a portion of said vaporized hydrocarbons other than the condensate reintroduced into the liquid mixture to separate said last-mentioned portion of said vaporized hydrocarbons into a condensate containing isobutane and a vapor containing propane, introducing said last-mentioned condensate into said liquid mixture, and withdrawing said last-mentioned vapor from the operation.

12. A process for alkylating a low molecular weight isoparaffin hydrocarbon with a low molecular weight olefin hydrocarbon in the presence of a liquid acid catalyst to form a higher-boiling paraffin hydrocarbon which comprises maintaining a liquid body comprising an intimate mixture of hydrocarbon reactants and acid catalyst and containing said low molecular weight isoparaffin hydrocarbon in a substantially high ratio to said olefin hydrocarbons, continuously withdrawing a portion of said liquid mixture containing hydrocarbons, continuously charging to said liquid mixture a hydrocarbon fresh feed comprising said low molecular weight olefin and isoparaffin hydrocarbons and lower-boiling normal paraffin hydrocarbons, maintaining the liquid mixture at alkylation conditions of temperature and pressure which permit vaporization of unreacted isoparaffin hydrocarbons and said lower-boiling normal paraffin hydrocarbons to facilitate maintaining the liquid mixture at the desired reaction temperature, withdrawing the vaporized hydrocarbons from said liquid mixture, cooling and condensing hydrocarbons thus removed, reintroducing condensate thus obtained into said liquid mixture, fractionating a portion of said vaporized hydrocarbons other than the condensate reintroduced into the liquid mixture to separate said last-mentioned portion of said vaporized hydrocarbons into a condensate containing substantially all the isoparaffin hydrocarbons and a portion of the said lower-boiling normal paraffin hydrocarbons contained therein and a vapor consisting of said lower-boiling normal paraffin hydrocarbons, said last-mentioned vapor being equivalent in quantity to the said lower-boiling paraffin hydrocarbons introduced into said liquid mixture as fresh feed, reintroducing said last-mentioned condensate into said liquid mixture, and withdrawing said last-mentioned vapor from the system.

BERNARDUS SELLMEYER.
